LEATHER COMPACTING AND BURNISHING
MACHINE

John J. Maciejowski, Ipswich, and Richard W. Daniels, Jr., Salem, Mass., assignors to United Shoe Machinery Corporation, Flemington, N. J., a corporation of New Jersey

Application August 26, 1949, Serial No. 112,446

14 Claims. (CL. 69—1)

1

This invention relates to machines for compressing and setting leather and more particularly to machines for compacting and burnishing heavy cattle hides which are to be used as sole leather.

In preparing heavy leather it is desirable to flatten out each hide and to impart uniform compactness to the fibrous structure and a smooth and burnished grain surface. Leather buyers require that the fat wrinkles be smoothed out and that the curling of the irregular edges of each work piece as caused by drying be eliminated insofar as is reasonably possible. The compacting of the fibers is carried out to increase the water resistance of the hide as well as to make it more durable and therefore more resistant to wear, both of those characteristics being highly desirable in hides to be used for shoemaking purposes.

In the past, the operation has been performed by moving and manipulating a hide beneath a freely-falling hammer until the entire work piece has been treated, or by subjecting the hide to the action of rollers pressing heavily upon it. The hammer type of machine requires close and expert supervision in the securing of uniform results and has not been accepted in this country. A common form of apparatus for rolling leather to secure the desired results is the swinging pendulum type of rolling machine which usually occupies space on two floors of a tannery. Such machines are bulky and are dangerous to operate, involve the use of much labor in handling the work, and the quality of results is unduly dependent upon the human factor. Another type of rolling machine employs a weighted roller which is passed back and forth over a leather supporting table by means of a horizontal rotating screw. The latter type of machine is slow in operation and the operator must maneuver each work piece for proper treatment and complete coverage.

It is an object of the present invention to provide an improved machine which will compact hides or wide pieces of heavy leather to a controlled extent independent of variations in hardness and/or thickness in the work. It is a further object of the invention to provide a machine utilizing multiple work treating tools including reciprocating compacting means in which machine the arrangement of parts is such that there is no possibility that machine lubricants may contact the work and discolor it. Still another object is the provision of a machine in which compacting of the work is done by recip-

2

rocating means or members in combination with anvil means and in which such compacting may be carried on simultaneously and in combination with a finishing of the grain surface by feeding and burnishing rolls.

To these ends, and in accordance with an important feature of the invention, means are provided for driving a reciprocating or compacting member through a predetermined length of stroke terminating short of an anvil contiguous to which a spread-out work piece may be fed for compacting treatment by the member.

Another feature of the invention is the arrangement of the lubricated surfaces of the machine with respect to the path of the work leading through the machine and also with relation to those machine surfaces which must be kept clean because of their possible contact with the work.

20 One other feature of the invention pertains to the combination of reciprocating means for the compacting of leather, together with cooperating rolls for feeding the work and burnishing the grain surface simultaneously with the compacting operation.

25 These and other important characteristics and features of the invention will now be described in detail in the specification and then pointed out more particularly in the appended claims.

30 In the drawings,

Fig. 1 is a front view of a machine in which the present invention is embodied;

35 Fig. 2 is a view in elevation, drawn to a larger scale, of the left end of the machine shown in Fig. 1, portions of the machine being broken away for ease of illustration;

Fig. 3 is an elevational view of a major portion of the right end of the machine;

40 Fig. 4 is an enlarged sectional view taken on the line IV—IV of Fig. 1, some exterior portions being omitted;

45 Fig. 5 is a plan view of a top portion of the machine with the right end broken away and some parts in section to show detail construction;

Fig. 6 is a sectional view along the line VI—VI of Fig. 4, drawn to a larger scale, illustrating one of the eight groupings of the compacting members and their cooperative anvils;

50 Fig. 7 is a sectional view of an arrangement employing a modified form of compacting member; and

Fig. 8 is a sectional view along the line VIII—VIII of Fig. 7.

55 In the illustrated construction the machine is

provided with two end castings 10 and 12 which are rigidly attached to and supported on three horizontal channel bars 14, 16 and 18 (Fig. 2) extending from side to side and beneath the machine. The upper end of the casting 10 has an overhanging lip 20 which extends inwardly and the casting 12 has an opposed and inwardly extending lip 22. Beneath the opposed lips 20 and 22 is mounted an upper horizontal casting 24 which is attached to the casting 10 by three bolts 26 (Fig. 2) and to the casting 12 by three bolts 28 (Fig. 3). Between the lip 20 and the casting 24 is a wedge shaped member 30. A similar wedge member 30 (Fig. 4) is located between the lip 22 and the right end of the casting 24. Each wedge member 30 is provided with a slot 32 (Fig. 2) through which a tightening screw 34 is arranged to pass. Each screw 34 is threaded into the block 24 and is provided with a small hand wheel 36 bearing a hub 38 which is adapted to rest on the top of the lip portion 20 or 22 for a purpose to be described.

The horizontal casting 24 has a depending vertical portion 40 (Fig. 4) extending transversely of the machine and from the casting 10 to the casting 12. The portion 40 includes triangular shaped end walls 41 (Fig. 2) and 45 (Fig. 4). Twenty equally spaced and vertically placed pins 42 are threaded into the top of the casting 24 at each side of the depending portion 40. It will be noted (Fig. 5) that the pins 42 in the front row are in staggered relation with the pins 42 in the back row. Each pin 42 is slotted at 44 to receive a locking bar 46. There are eight of these locking bars 46, as the pins 42 and their associated parts are arranged in eight groups with five pins in each group. There are two short pins 47 (Fig. 5) driven through holes provided in each bar 46 to prevent the latter from being displaced. Each vertical pin 42 has an annular shoulder 43 and also a lower and reduced end portion 48, the latter serving to prevent horizontal displacement of a coil spring 50.

Bolts 52 (Figs. 4 and 6) are utilized at each side of the depending portion 40 to hold four anvil retaining castings 54 in position. There are eight such castings—one for each group of five anvils. Each casting 54 is bored for the reception of five cylindrical sleeve inserts 56 (Fig. 4) and these serve as guiding means for anvils 60. In the preferred construction each anvil 60 is cylindrical for the major portion of its length and carries a rectangular flange 62 of such dimensions that the five flanges 62 of each casting 54 are in abutting relation with one side of each flange in contact with a vertical surface of the casting 54. It will be understood that each of the anvils 60 is in alinement with a pin 42. Each anvil 60 is recessed freely to receive the major portion of one of the coil springs 50. A gasket 70 of resilient shock absorbing material, such as rubber or neoprene impregnated fabric, is inserted between each flange 62 and the casting 54. The lower end of each tool or anvil 60 is narrowed down as clearly depicted in Figs. 4 and 6 to present an elongated work contacting or compacting surface with a width as measured in the direction of feed that is smaller than the width of the work contacting surface of each opposing tool hereinafter to be described. All edges of the lower end of the anvil 60 are smoothly rounded off to prevent damage to or marking of leather coming in contact with them and Figs. 4 and 6 show that the anvil contours are curved

to provide proper concentration of pressure upon the work, particularly as considered in the direction of feed.

A horizontal work guiding plate 72 with upturned edges is mounted immediately below the eight castings 54, and this plate 72 is supported from the depending portion 40 by means of ears 74 and bolts 76 (Fig. 4). The arrangement is such that each anvil 60 is free of the plate 72 (because of the clearance provided) for motion with relation to that plate.

The top of the horizontal casting 24 is provided with two cylindrical bosses 80 (Fig. 1) and one centrally located and elongated boss 82 (Fig. 5). The boss 82 is provided with an undercut slot 84 adapted to receive the head of a vertical bolt 86. A hand wheel 90 is threaded onto the bolt 86 and has a hub 92 which is arranged to bear downwardly against the overlapping inner ends of two transversely extending bars 100 and 102 (Fig. 1). Each of the last mentioned bars is provided with a slot 103 (Fig. 5) through which bolt 86 passes. The bar 100 is pivoted on a bolt 104 which is threaded into one of the bosses 80. The bar 102 is pivoted on a bolt 106 (Fig. 1) which is threaded into the other boss 80. The outer end of the bar 100 is connected to the left end wedge member 30 by a ball-and-socket joint 110 (Fig. 5). The bar 102 is connected to the wedge member 30 at the right end of the machine by a similar socket joint 112 (Fig. 1).

A second horizontal work guiding plate herein shown as 114 (Figs. 4 and 6) is mounted beneath and in spaced relation with the plate 72 to define a passage for work being fed through the machine in a spread-out condition and in a path contiguous to the anvils 60. The front and rear edges of the plate 114 are bent downwardly to a slight extent as seen in Fig. 4 and the plate is provided with ears or lugs 116 through which bolts 118 are passed to attach the plate above and in spaced relation to a main casting 120 (Figs. 1 and 4) of the machine. The plate 114 has holes 122 in alinement with the anvils 60.

The main casting 120 per se is an open-ended box-like structure. It is provided with end flanges 124 and 126 (Fig. 1) through which bolts 128 are passed for holding the casting in position upon and in sealed relation with the end castings 10 and 12. The upper wall 130 (Fig. 4) of the casting 120 is arranged to receive forty compacting members 132 for vertical reciprocation. Each of the compacting members 132 has a flat head 134 having rounded edges which is adapted freely to pass through one of the holes 122 in the plate 114. The work contacting area of the head 134 is larger than that of the opposing tool or anvil 60. Each compacting member 132 is recessed at 136 to reduce weight and bears transverse vents 138 as well as cut-out portions 140 to promote lubrication. The bottom end of each compacting member 134 is slotted to form two depending ears through which a pin 142 is passed. There is one pin 142 for each set of five compacting members 132. A link 144 is pivoted on the pin 142 for each of the compacting members 132 and the bottom end of each link is pivoted on a shaft 146 passing through extending portions of one of two arms 150 which are parts of a casting 152 pivotally mounted on a shaft 154. As seen in Figs. 4 and 6, there is a casting 152 for each group of ten compacting members 132 and one arm 150 for each set of five compacting members. The ends of the shaft 154 are mounted on the end castings 10

and 12, as will be understood. Each casting 152 has a third or a downwardly inclined arm 156 through which a pin 160 passes and upon which an arm 162 is adapted to pivot. This arm 162 is a portion of a cylindrical member 164 (Fig. 4) forming part of an eccentric arrangement 166 mounted on the shaft 168. The shaft 168 is keyed to the eccentric arrangement in such a way that the relation of the eccentric to the compacting members may be adjusted to four angular positions.

Two cooperating rolls 170 and 172 are mounted on the front of the machine with the bite of those rolls just in front of the work receiving space or passage between the horizontal plates 12 and 14. The roll 170 is uppermost and is mounted in conventional bearing blocks located on the end castings 10 and 12. This roller 170 is provided with a surface layer of yielding material 174 such as rubber. The roller 172 bears a hard or polished steel surface 176 and is journaled in the upper ends of arms 180 and 182. The arm 180 is pivoted by means of an eccentric adjusting device 186 to the end casting 10. The arm 182 is pivoted on a similar device 188 to the casting 12. The center of the device 188 is not in the same plane as are the centers of the rolls 170, 172 and for this reason a toggle action is provided for closing the rolls. Straightening of the toggle is approached when the roll 172 is swung toward the front of the machine. Such swinging is effected by springs 190 two of which are mounted to abut a shoulder (not shown) on each of the end castings 10 and 12.

Similar cooperating rolls are mounted on the rear of the machine and the upper roll 194 is covered with yielding rubber-like material. The lower roll 196 is smooth surfaced and is preferably of steel and is mounted on arms 198 and 199 pivoted on eccentric adjusting devices 200 so that swinging of the roll 196 toward the front of the machine will tend to close the bite of the rolls and straighten the toggle arrangement. Four springs 202 are used to urge the roll 196 forwardly.

A plate 210 (Fig. 2) is bolted to the front portion of the casting member 10 and a similar plate 212 (Fig. 3) is bolted to the casting 12 and these plates serve to support a table 213 which is arranged in inclined position on the machine with its upper and rearmost edge close to the bite of the rolls 170 and 172. A sheet metal member 214 (Fig. 1) is mounted in front of the roller 170 and above and in spaced relation with the rear and upper edge of the table 213.

A motor 300 (Fig. 1) is mounted on the horizontal base members or channel bars 14 and 16, and its shaft is arranged to drive a sprocket 302 which in turn drives a chain 304 and a sprocket 306 keyed to the shaft 308 of the upper and rear roller 194. The other end of the roller 194 is provided with a stub shaft 310 (Fig. 1) to which is keyed a sprocket 312. The sprocket 312 is in engagement with a chain 314 which serves to drive a sprocket 316 attached to the shaft 318 of the roller 170. Pivoted near the top of the end casting 12 and at 320 and 322 (Fig. 3) are two horizontal arms 324 and 326. The arm 324 is urged upwardly by springs 330 (Fig. 2) and the arm 326 is urged upwardly by springs 332. At the outer end of the arm 324, two sprockets 331 are pivoted and at the outer end of the arm 326 are pivoted two sprockets 333. Two chains 340 are arranged to be driven by the sprockets 331 and engage the teeth of sprockets 342 (Fig.

5) which are arranged to rotate together with the sprocket 316 and the chains 340 also pass around a pair of sprockets 344 attached to the shaft 346 of the roller 172. Two chains 350 are in engagement with the sprockets 333 and engage the teeth of sprockets 352 (Fig. 3) which are adapted to rotate with the sprocket 312. The chains 350 also pass around a pair of sprockets 354 and thereby drive the rear lower roller 196.

10 A second motor 400 is mounted in the base of the machine and through multiple pulleys 402, 404 and cooperating belts 406 is arranged to rotate the main drive shaft 168 thereby bringing about the reciprocation of the forty compacting members 132.

15 The main casting 120 is attached (preferably with gaskets interposed) to the end castings 10 and 12 and serves as a reservoir for lubricating oil and the rapid revolution of the eccentrics 166 upon rotation of the shaft 168 causes sufficient splashing action to effectually lubricate areas subject to friction such as the exterior vertical wall surfaces of the reciprocating compacting members 132.

20 With the construction shown there is a predetermined minimum clearance between the flat tops of the compacting members 132 and the bottoms of the anvils 60. It will be appreciated that the adjustment of this clearance is critical and for this reason the wedge members 30 are provided. If the bolts 26, 28 and the hand wheels 36 and 90 are loosened the threaded rod 86 may be pushed forwardly or rearwardly and thereby move the wedges 30 in unison and to the same extent. When the adjustment of the casting 40 is effected then the hand wheels 90 and 36 may be tightened to lock the wedge members 30 in their proper positions and then the bolts 26 and 28 may be tightened to hold the casting 24 in its newly adjusted position.

25 The eight horizontal bars 46 are used to hold the vertical pins 42 in adjustment so that the anvils 60 are properly spring-loaded. The slots 44 and the bars 46 provide a simple means whereby the loadings of the springs 50 may be adjusted through increments of 180°.

30 As stated heretofore, the vertical pins 42 (Fig. 5) are in staggered relation. The anvils 60 and compacting members 132 are in alignment with the pins 42 and are therefore also in staggered relation. The purpose of such relation is obvious—to make the action of the compacting members effective across the full width of each work piece passed through the machine.

35 With some types of leather and for particular uses it may be preferred that a group of the compacting members should be effective as a unit. In such event a construction such as shown in Figs. 7 and 8 may be preferred. Each compacting member may include a number of vertically reciprocable intermediate plungers 420 and end plungers 422. These plungers are substituted for the compacting members 132 of Figs. 4 and 6 and a row of the plungers (in groups of five, twenty or any other number) are joined together by a horizontal flat bar or member 424. All the plungers are provided with undercut slots 426 into which T projections 428 (for the plungers 420) and 430 (for the end plungers 422) are adapted to be received. The T projections are integral with the bar 424. Each end plunger 422 is bored as at 432 to receive a headed pin 434 with its head extending into a slot 436 formed in a T projection 430. It will be understood that the plungers 420, 422, the bar 424 and

the pins 434 are assembled as a unit prior to insertion of the plungers into the casting 120. With this type of construction one bar 424 may be used in place of the twenty separate compacting members 132 in the front or rear row or two bars 424 may be used to take the place of all forty compacting members 132. Variations in this regard will depend upon the type of work and the sizes of work pieces to be treated.

In operating the machine the workman presents a hide in spread-out condition over the table 213 and, assuming that the motors 300 and 400 are in operation, he presents the leading edge of the work piece W (Fig. 4) to the bite of the rolls 170 and 172 with the grain side down and in contact with the smooth steel surface 176 of the roll 172. The arrangement of the driving mechanism is such that the upper rolls 170 and 194 rotate relatively slowly and determine the rate at which the work piece W is fed through the machine. The driving mechanism is such that the surface of the steel roller 172 is driven at less feet per minute than the surface of the roller 170 and this brings about a burnishing action with respect to the grain surface of the work piece. As the work piece is interposed and passed between the compacting members 132 and the anvils 60 the compacting members operate with a predetermined length of stroke which is not affected by varying characteristics such as localized soft spots in the leather. The work piece W is guided through the machine and discharged by the rolls 194 and 196. The lower rolls 172 and 196 bring about the burnishing and general smoothing action of the grain surface and the compacting members 132 do the major portion of the work in compressing the leather.

With the machine illustrated, and for the treatment of sole leather, best results have been obtained using a clearance of $\frac{1}{2}$ " between each anvil 60 and its corresponding compacting member 132, a speed of 1900 R. P. M. for the shaft 168, and a feed speed of about 30 feet per minute with the lower rolls having a 10% slower surface speed than the upper rolls. The spring loading will be varied dependent upon the type of leather being treated. With sole leather and an anvil of $1\frac{1}{8}$ " diameter of the design illustrated, a suitable spring preloading for that anvil has been found to be 400 pounds.

It will be noted that no feeding devices are required to adapt the machine for treatment of a particular work piece. As above referred to, the maximum extent of action of the compacting member or members is definitely predetermined and is unaffected by soft spots in the work. The latter characteristic of the machine gives control of the operation and is conducive to uniformity in the work done. The lubricated parts of the machine are located below the work treatment zone and the arrangement of the elements such as plate 114 is such that lubricating oil will not contact or mar the leather finish.

The steel rolls 172 and 196 have a burnishing effect on the grain side of the hide W and the result is not adversely affected by the action of the compacting members 132 as the major portion of the compacting is done from the flesh side of the work. This is due to the relative proportions given to the work contacting areas of the anvils and the compacting members. Actually, and in the machine illustrated, the compacting members serve as backing members and the anvils do the indenting or compacting from the flesh side of the work. Obviously an

arrangement opposite to this may be had and such concept falls within the scope of the present invention. It is clear that, in all cases, the indenting for compacting purposes should be on the flesh side of the work and the burnishing rolls should contact the grain side.

Having described our invention, that we claim as new and desire to secure by Letters Patent of the United States is:

1. In a machine for compacting and burnishing hides, a frame, anvil means on said frame, reciprocable means associated in cooperative relation with said anvil means and having a length of stroke terminating short of said anvil means, and means for feeding a spread-out work piece in a path leading between said anvil means and said reciprocable means, said feeding means comprising two cooperating rolls adapted to be driven at different speeds and one of said rolls having a surface of yielding material for engaging one side of said work piece and the other roll having a hard and smooth surface for burnishing the other side of said work piece.
2. In a machine for compacting hides, a frame, anvil means on and yieldable with respect to said frame, vertically reciprocable means arranged beneath and in cooperative relation with said anvil means and having a predetermined length of stroke terminating short of said anvil means to give a definite clearance space, parallel and spaced work-guiding plates arranged on said frame, one of said plates being immediately above and the other immediately below said space, and means for feeding a spread-out work piece between said plates and into said space for compacting by and between said anvil means and said reciprocable means.
3. In a machine for compacting hides, a frame, anvil means on and yieldable with respect to said frame, reciprocable means arranged below and in cooperative relation with said anvil means, said reciprocable means having a predetermined length of stroke terminating short of said anvil means, and a cooperating set of work feeding rolls in front and also in back of the machine to feed a work piece in a path leading between said anvil means and said reciprocable means.
4. In a machine for compacting and burnishing hides, a frame, anvil means on and yieldable with respect to said frame, reciprocable members arranged below and in cooperative relation with said anvil means and having a predetermined length of stroke terminating short of said anvil means to give a definite clearance space, a horizontal work guiding plate mounted immediately below said clearance space, and means for feeding and discharging a spread-out work piece through said clearance space, said work feeding and discharging means comprising two sets of cooperating rolls, each of said sets having an upper roll with a surface material for engaging the work without slippage and a lower roll with a smooth and hard surface to produce a burnishing effect on the work.
5. In a machine for compacting hides, a frame, anvil means on said frame, reciprocable compacting means arranged below and in cooperative relation with said anvil means and extending across the machine the full width of a work piece to be treated, and cooperating work feeding rolls to feed a work piece in a path leading between said anvil means and said reciprocable means, one feeding roll having a surface of yielding material and another roll arranged to cooperate with said one feeding roll and having a hard surface,

6. In a machine for compacting hides, a frame, anvil means and reciprocable compacting means extending in cooperative relation across the machine frame the full width of a work piece to be treated, a set of work feeding rolls in front and also in back of said machine to feed work along a path leading between said anvil means and said reciprocable means, the upper roll of each set being fixed in position on said frame and having a surface of yielding material, the lower roll of each set having a hard surface, and means for supporting and urging each of said lower rolls yielding upward into cooperative relation with its corresponding upper roll.

7. In a machine for compacting hides, a frame, anvil means on said frame, reciprocable compacting means arranged in cooperative relation with said anvil means and extending across the machine the full width of a work piece to be treated, a cooperating set of work feeding rolls located at each side of the said anvil and compacting means and arranged to feed a work piece in a path leading between said anvil means and said compacting means, one roll of each of said sets having a hard surface to give a burnished effect on the grain side of the work and the work contacting areas of the anvil means and compacting means being so proportioned that the major portion of the compacting is done from the flesh side.

8. In a machine for compacting hides, a frame, multiple work treating tools on said frame comprising anvils and reciprocable members, said members being arranged to oppose and cooperate with said anvils, means for feeding a spread-out work piece in a path contiguous to said anvils, some of said tools having work contacting surfaces of curved contour with narrow portions of said surfaces being flat and extending transverse to and at one side of said path and the opposed tools having relatively broad and substantially flat work contacting surfaces arranged on the other side of said path.

9. In a machine for compacting hides, a frame, means on said frame for feeding a spread-out work piece in a path leading through the machine, at least one row of anvils resiliently mounted on and with respect to said frame and said row being arranged transversely and contiguous to said path, and reciprocable means with a predetermined length of stroke terminating short of said anvils, said anvils and reciprocable means being effective on the full area of said work piece as the latter is fed through the machine.

10. In a machine for compacting hides, a frame, means on said frame for feeding a spread-out work piece in a path leading through the machine, a row of anvils resiliently mounted on and with respect to said frame and arranged transversely and contiguous to said path, reciprocable means with a predetermined length of stroke terminating short of said anvils, the work contacting area of the anvils and reciprocable means being small on one side of said path and larger on the other side, and said anvils and reciprocable means extending the full width of the work piece.

11. In a machine for compacting hides, a frame, means on said frame for feeding a spread-out work piece in a path leading through the machine, a reciprocable flat bar arranged transverse and contiguous to said path, a row of resiliently mounted anvils arranged in cooperative relation with said bar and on the opposite side of said path, the said anvils having work contacting surfaces with a width as measured in the direction of feed which is smaller than that of the work contacting surface of the said bar.

12. In a machine for compacting hides, a frame, means on said frame for feeding a spread-out work piece in a path leading through the machine, tools on said frame comprising reciprocable flat bars arranged transverse to and at one side of said path and anvils arranged in cooperative relation with said bars and at the other side of said path, each of said anvils having a work contacting surface with a width as measured in the direction of feed that is smaller than the width of the work contacting surface on the bar cooperating with that anvil.

13. In a machine for compacting hides, a frame, means on said frame for guiding a spread-out work piece along a desired path, a row of tools at one side of said path and transverse thereto, each of said tools having a work contacting surface of curved contour in the direction of feed, a member with a flat work contacting surface of greater width mounted in cooperative relation with said row of tools and at the other side of said path, and means for reciprocating the tools and member relatively for compacting the said work piece as it is fed in said path.

14. In a machine for compacting hides, a frame, means on said frame for guiding a spread-out work piece along a desired path, rows of resiliently mounted anvils with work contacting surfaces of curved contour arranged transverse to said path and at one side thereof, and reciprocating members at the other side of said path having flat surfaces opposed to said anvils, each of the said flat surfaces being wider as measured in the direction of feed than each of the similarly measured work contacting surfaces on the said anvils.

JOHN J. MACIEJOWSKI.
